CLAIM

The ornamental design for the display screen with graphical user interface for a laboratory instrument, as shown and described.

DESCRIPTION

FIG. 1 is a front view of a first embodiment of the display screen with graphical user interface for a laboratory instrument;

FIG. 2 is a front view of a second embodiment thereof; FIG. 3 is a front view of a third embodiment thereof; FIG. 4 is a front view of a fourth embodiment thereof; FIG. 5 is a front view of a fifth embodiment thereof; FIG. 6 is a front view of a sixth embodiment thereof; FIG. 7 is a front view of a seventh embodiment thereof; FIG. 8 is a front view of an eighth embodiment thereof; FIG. 9 is a front view of a ninth embodiment thereof; and FIG. 10 is a front view of a tenth embodiment thereof.

FIG. 10 is a front view of a term embodiment thereof. The interior broken lines in the figures illustrate portions of the graphical user interface that form no part of the claimed design. The broken line perimeter in the figures is included for the purpose of showing a display screen and forms no part of the claimed design.
